UNITED STATES PATENT OFFICE

ESTA E. YOUNT, OF NEAR DAYTON, OHIO

DESIGN FOR A COMBINATION MERCHANDISE DISPLAY AND LIQUID DISPENSING CABINET

Application filed October 31, 1932. Serial No. 45,666. Term of patent 7 years.

To all whom it may concern:

Be it known that I, ESTA E. YOUNT, a citizen of the United States, residing in the county of Montgomery, near the city of Dayton, and State of Ohio, have invented a new, original, and ornamental Design for a Combination Merchandise Display and Liquid Dispensing Cabinet, of which the following is a specification, reference being had to the accompanying drawing, forming part thereof.

The figure is a perspective view of a combination merchandise display and liquid dispensing cabinet, showing my new design.

I claim:

The ornamental design for a combination merchandise display and liquid dispensing cabinet, as shown.

ESTA E. YOUNT.
